(57) **CLAIM**

The ornamental design for a flexible package, as shown and described.

DESCRIPTION

FIG. 1 is a perspective view of a flexible package showing my new design;

FIG. 2 is a front elevational view thereof, the rear elevational view being a mirror image;

FIG. 3 is a right side elevational view thereof, the left side elevational view being a mirror image;

FIG. 4 is a top plan view thereof, the bottom plan view being identical; and,

FIG. 5 is a perspective view of the flexible package of FIG. 1 showing of edible crackers contained therein for illustrative purpose only and forming no part of the claimed design.

In FIGS. 1, 2, 4 and 5, stippling is used to represent sealed portions of the package and not surface texture characteristics. In FIGS. 1, 2 and 5, the broken lines indicate a tearable line of weakness in the package. In all the Figures, conventional transparency shading is used to represent transparent portions.
